UNITED STATES PATENT OFFICE

NORMAN W. HILL, OF EAST HAMPTON, CONNECTICUT, ASSIGNOR TO THE N. N. HILL
BRASS COMPANY, OF EAST HAMPTON, CONNECTICUT, A CORPORATION

TOY TELEPHONE

Application filed April 28, 1930. Serial No. 447,814.

This invention relates to an improvement in toy telephones and particularly to toy telephones which simulate the "continental" type, such, for instance, as is shown and described in application filed by me on January 5, 1930, Serial No. 422,316.

The object of this invention is to provide a toy telephone of the type described which can be produced at a low cost for manufacture, and the invention consists in the construction as hereinafter described and particularly recited in the claims.

In the accompanying drawings:

Fig. 1 is a side view of a toy telephone constructed in accordance with my invention;

Fig. 2 is a front view of the same;

Fig. 3 is a broken front view, with the gong of the bell removed;

Fig. 4 is a sectional view on the line 4—4 of Fig. 2;

Fig. 5 is a perspective view of the base of the bell, detached; and

Fig. 6 is a perspective view of the bell-operating rack, detached.

In carrying out my invention, I employ a base 10 of any suitable design, and mounted on the base 10 is a post 11 carrying a yoke 12 at its upper end. Within the yoke is a cradle 13 upon which the handle 14 of a telephone-instrument rests. At one end of the handle is the simulation of a receiver 15 and at the other end the simulation of a transmitter 16, and the receiver 15 is connected with the base 10 by a cord 17. The cradle is guided for vertical movement by a pin 18 which extends through the yoke 12 and into a recess 19 formed for it in the upper end of the post 11.

Connected at the center of the cradle is an arm 20 which projects outward through a slot 21 formed in a vertically-arranged rack-bar 22 which extends through the base 23 of a bell 24, which is of the usual bicycle-bell type and is attached to the front of the post by a staple 25 secured to the base 23.

The teeth 26 of the rack mesh with a small pinion 27 which is formed with, or connected to, a gear 28 meshing with a central pinion 29 mounted on a post 30 which also carries strikers 31. The rack is also formed with a slot 32 through which the central post 30 extends,

so that the rack is guided for vertical movement and held in mesh with the pinion 27. This rack is held in its raised position by a spring 33 connected with the base and with the lower end of the rack, which is provided with a hook 34 for this purpose. The lower end of the rack is turned rearward, forming a lip 35 which rides against the inner surface of the base 23 to assist in holding the rack in a vertical position.

If the base is provided with dial-mechanism 36, such dial-mechanism may be released by the pin 18 extending through the post 11, as indicated by broken lines in Fig. 4, to operate in the same manner as shown and described in the above-mentioned application.

The telephone-instrument rests upon the cradle, and a downward movement of the instrument depresses the cradle, moving the rack downward and causing the bell to ring, or the instrument may be removed and a downward pressure by the fingers upon the cradle will also ring the bell.

It is obvious that various bell-mechanisms may be employed, as the particular construction of the bell is immaterial to this invention.

I claim:

1. In a toy telephone-set, the combination with a base, of a bell-support uprising therefrom, a mechanically-operated bell secured to the said bell-support, means for operating the bell, and a horizontally-arranged receiver-support cooperating with the said bell-operating means to sound the bell, the said receiver-support being centrally located above the top of the said bell-support.

2. In a toy telephone-set, the combination with a base, of a post mounted thereon, a vertically-movable cradle located above the top of said post, a mechanically-operated bell secured to said post, and vertically-movable means connected with said cradle and cooperating with the said bell for sounding the same.

3. In a toy telephone-set, the combination with a base, of a vertically-arranged post mounted thereon, a stationary yoke secured to the top of the said post, a vertically-movable cradle located within said yoke, a bell mounted on the post below the said yoke, and

vertically-movable means connected with the cradle for operating said bell.

4. In a toy telephone-set, the combination with a base, of a post mounted thereon, a vertically-movable cradle located above the top of said post, a bell-mechanism secured to the said post, including a base, a vertically-movable rack extending into said base and into engagement with one of the pinions of the bell-mechanism, and a connection between the upper end of the rack and the said cradle.

In testimony whereof, I have signed this specification.

NORMAN W. HILL.
